JOHN HAYS HAMMOND, JR., OF GLOUCESTER, MASSACHUSETTS.

SYSTEM OF TELEDYNAMIC CONTROL.

1,295,741.

Specification of Letters Patent.

Patented Feb. 25, 1919.

Application filed January 21, 1913, Serial No. 743,270. Renewed January 4, 1919. Serial No. 269,657.

To all whom it may concern:

Be it known that I, JOHN HAYS HAMMOND, Jr., a citizen of the United States, residing at Gloucester, in the State of Massachusetts, have invented certain new and useful Improvements in Systems of Teledynamic Control, of which the following is a specification, reference being had to the accompanying drawings, forming a part

10 thereof.

This invention relates to systems for controlling and operating mechanisms from a distance, and relates more particularly to systems in which pneumatic or hydraulic machinery for operating the steering gear and engines of torpedoes and other vessels and the like, is controlled by radiant energy transmitted from a distant station.

In the accompanying drawings:—

20 Figure 1 shows a diagrammatic view of one form of a receiving station on my system employing electric and pneumatic apparatus.

25 Fig. 2 gives a more detailed view, partly diagrammatic, of part of the apparatus on my system on board a torpedo or some other vessel.

In Fig. 1, A is an antenna connected to earth E through the inductance coil L and 30 variable condenser C, and inductively coupled to the oscillation circuit L¹ C¹ by means or the coils L and L¹, C¹ being a variable condenser, and the circuit L¹ C¹ being in tune with the antenna circuit. D is a stopping condenser and R a rectifier, by means 35 of which unidirectional current impulses are supplied to the coil L², which is inductively coupled to the oscillation circuit L³ C², consisting of the coil L³ and the variable condenser C², this latter oscillation circuit being 40 tuned to the group frequency or amplitude variation frequency of the transmitting station. D¹ is a stopping condenser and R¹ a rectifier, by means of which unidirectional 45 currents are supplied to the sensitive relay K, which is connected with the battery B and which actuates the stronger relay K¹. Relay K¹ is connected with the battery B¹ and actuates the electromagnet M, which in 50 turn operates the rotary valve 5. Valve 5 controls the flow of a fluid, such as compressed air or water, or any other suitable fluid from the tank T through pipe 18 to the pipes 14, 15, 16 and 17. N is an auxiliary piston which can also operate the

valve 5 under certain circumstances, as will hereafter be described.

In Fig. 2, 5 is a rotary cylindrical valve operated by the electromagnet M. This valve, instead of having electrical contacts 60 upon it, has ports or openings, such as 19, 20, 21 and 22, which control the flow of a fluid. The electromagnet M moves the valve 5 step by step. The ports or openings of the valve are in sets, corresponding to definite 65 positions of the valve, and between each set of ports is a neutral position of the valve, in which none of the ports is operatively connected with the working fluid and piping system. Ports 20 and 22 are connected by 70 means of the pipe 18, with the tank T or source of supply of the working fluid. Ports 19 and 21 are exhaust ports leading to the outer air. There are other similar sets of 75 ports in the valve, which are not shown.

Pipes 14, 15, 16 and 17 can be operatively connected with ports 19, 20, 21 and 22, respectively. Pipes 14 and 17 lead to the openings or ports 30 and 28, respectively, in cylinder 4, and pipes 15 and 16 lead to the 80 openings 27 and 29, respectively, in cylinder 3. The spring 31 tends to move the piston 3^a toward the openings 27 and 29, and the opening or port 23 is made small so that air or other fluid can enter and escape through 85 it only slowly, and any movement of the piston 3^a toward the right will therefore be retarded. Spring 32 and opening 24 in cylinder 4 have similar functions to spring 31 and opening 23 in cylinder 3. Piston rod 90 3^b is operatively connected with the ports 10 and 11, which open and close the pipes 25 and 26, respectively. Pipe 25 connects pipe 15 with cylinder 1, and 26 is an exhaust pipe leading from cylinder 1 to the outer 95 air.

Piston 4^a is connected to piston rod 4^b, which is operatively connected with ports 12 and 13, which open and close the pipes 34 and 35, respectively. Pipe 34 connects pipe 17 100 with cylinder 2, and 35 is an exhaust pipe leading from cylinder 2 to the outer air.

Cylinder 1, by means of the piston 1^a and piston rod 1^b, is operatively connected with the helm 6, and cylinder 2, by means of the 105 piston 2^a and piston rod 2^b, is also operatively connected with the helm 6, which is connected with the rudder, the latter not shown. The helm 6 is arranged to swing about a fixed pivot 6' and the spring 7 110

tends to keep the helm 6 in a central position.

- The bar 48 is attached to the helm 6, and has projecting end pieces 46 and 47. Pipes 5 40 and 45 are connected with the tank T or other source of supply of the working fluid. Valve 39 opens and closes pipe 40, and is operated by means of the bent lever 38. Pivoted on this bent lever is a movable piece 10 36, which is normally held against a stop 49 by the spring 37. When end piece 46 is moving to the right, piece 36 is momentarily depressed, but as soon as 46 has passed it is restored to its original position by 15 spring 37. When, however, 46 is moving to the left and strikes 36, the latter presses against stop 49 and causes the bent lever 38 to open valve 39. The momentum of the helm and its attached mechanisms will then 20 carry the bar 48 and its end piece 46 on until the piece 36 is pushed so far to the left that piece 46 can move over and past it, when the bent lever 38 and valve 39 will drop back to their original positions.
- 25 When valve 39 is open, the air or other working fluid, is admitted to the pipe 8 which leads to the auxiliary piston N. Piston N then operates the rotary valve 5 and causes the latter to move to a neutral position and so stops the whole system.

Valve 44 opens and closes pipe 45 and is operated by means of the bent lever 43. Pivoted on this bent lever is a movable piece 35 41, which is normally held against a stop 50 by the spring 42. When end piece 47 is moving to the left, piece 41 is momentarily pushed aside, but as soon as 47 has passed, it is restored to its original position by spring 42. When, however, 46 is moving 40 to the right and strikes 41, the latter presses against stop 50 and causes the bent lever to open valve 44. The momentum of the helm and its attached mechanisms will then carry the bar 48 and its end piece 47 on until the 45 piece 41 is pushed so far to the right that piece 47 can move over and past it, when the bent lever 43 and valve 44 will drop back to their original positions.

When valve 44 is open, the air, or other 50 working fluid is admitted to the pipe 8 which leads to the auxiliary piston N. Piston N then operates the rotary valve 5 and causes the latter to move to a neutral position and so stops the whole system.

55 In this way the above described mechanism acts as a center stop, to hold the helm and rudder in a central position when they return from a port or starboard position.

When compressed air is used as the working fluid, the method of operation of my system is as follows:—In Fig. 2 the electromagnet M has caused the valve 5 to rotate into a position where port 22 connects the supply pipe 18 with the pipe 17 leading to 60 the cylinder 4, and where the port 21 connects

exhaust pipe 16 leading from cylinder 3 to the outer air. The exhaust pipe 14 from cylinder 4 is closed. Compressed air will enter cylinder 4 through pipe 17 and port 28 and piston 4^a will begin to move to the 70 left. But it can move only slowly, as the air to the left of the piston will be compressed and cannot escape rapidly through the small opening 24. When piston 4^a finally reaches the left end of its stroke, it will cause port 75 13 to open and port 12 to close. Port 13 connects pipe 17 with pipe 34, thus allowing the compressed air to enter cylinder 2, and as the exhaust pipe 35 is closed, the piston 2^a will be moved toward the left and will 80 move helm 6 to the left.

If is desired to stop the helm at any particular position, the electromagnet M should be energized by another impulse, thereby causing the rotary valve 5 to move to a neutral position where none of its ports will be connected with pipes 14, 15, 16 and 17. The intake and exhaust pipes of cylinders 4 and 2 will therefore be closed, and pistons 4^a and 2^a will be held stationary; the whole system will be locked and the helm and rudder will be held in whatever position they happen to occupy.

When it is desired to move the rudder back to its central position, another impulse 85 should be sent, energizing magnet M, and causing the latter to rotate valve 5 to its next operative position, where ports 19 and 20 are connected, respectively, with pipes 14 and 15. Compressed air will pass from supply pipe 18 through port 20, pipe 15 and port 27 into cylinder 3, thus moving piston 3^a to the right; and at the same time cylinder 4 will exhaust through port 30, pipe 14 and port 19, and piston 4^a will be pushed to 100 the right by spring 32. When piston 4^a moves to the right, port 12 will be opened, so that cylinder 2 can exhaust through pipe 35.

As piston 3^a moves to the right, exhaust 110 port 11 will be closed and intake port 10 will be opened, thus allowing compressed air to enter cylinder 1 through pipe 25 and causing piston 1^a to move toward the right. Helm 6 will therefore be moved to the right, 115 toward its central position. As the projecting piece 47 at the end of bar 48 moves to the right, it will engage with piece 41 and so cause the bent lever 43 to open valve 44 and permit compressed air to pass through 120 pipes 45 and 8 to pneumatic piston N. Piston N will cause rotary valve 5 to move to a neutral position and thus lock the whole system, but the inertia of the helm and the attached apparatus will cause contact piece 125 47 to move far enough to the right to pass over movable piece 41, as previously described, and the helm will reach its central position before stopping. In this way, the rudder will be caused to stop automatically 130

in a central position; and the same series of operations can be made to occur if the rudder moves in the opposite direction.

The position of the helm can be regulated 5 as desired. For instance, if it is to be moved a little to the left, compressed air is admitted to cylinder 2, as above described, and after piston 2^a has moved the helm 6 to the angle desired, another impulse is 10 sent from the transmitting station, thus energizing the electromagnet M and causing it to rotate the valve 5 to a neutral position. If then it is desired to move the helm still more to the left, the electromagnet M 15 is energized three times in rapid succession, with the following results: The first time it is energized, it will cause the valve 5 to move to the operative position where compressed air is admitted to cylinder 3 and 20 exhausted from cylinder 4, but as pistons 3^a and 4^a can both move only slowly, owing to the slow passage of air through the small openings 23 and 24, respectively, they will not have moved far enough to cause com- 25 pressed air to be admitted to cylinder 1 and exhausted from cylinder 2 before the second impulse energizes electromagnet M and causes it to rotate valve 5 to a neutral position. The third impulse will then energize M again and cause it to rotate valve 5 to an operative position where compressed air is admitted to cylinders 4 and 2 and exhausted from cylinders 3 and 1, and valve 5 can be kept in this position until the helm 30 is moved still farther to the left to any angle desired.

A similar course of procedure is followed with the opposite operative positions of valve 5 when it is desired to move the helm 40 to the right, and it is possible, as shown, to cause the rudder to assume any angle desired.

I do not limit myself to the use of air as a working fluid, but may use any other suitable gas or any suitable liquid, nor do I limit myself to a steering device for torpedoes or other vessels, but may put my invention to any use desired; and in general I do not confine myself to the particular apparatus and mechanisms here shown, but various changes and modifications, within the capacity of those skilled in the art, may be made in the particular apparatus shown and described herein, without departing from 50 the spirit of my invention, provided the means set forth in the following claims be employed.

Having thus described my invention, I claim:

1. A system for controlling moving vessels by radiant energy, comprising in combination, a receiving circuit responsive to radiant energy, a vessel having a compressed fluid operated prime mover provided with a mem- 5 ber movable to and fro by said motive fluid,

and also having an intake and an exhaust, means operable through the instrumentality of said receiving circuit for opening said intake to obtain movement of said member in one direction and to open the exhaust to 70 obtain movement thereof in the opposite direction, steering means, and operative connections between said movable member and said steering means.

2. A system for controlling moving vessels by radiant energy, comprising in combination, a receiving circuit responsive to radiant energy, a vessel having a compressed fluid operated prime mover provided with an intake and an exhaust for the motive 80 fluid and also provided with a member movable in one direction when the intake is open and movable in another direction when the exhaust is open, means operable through the instrumentality of said receiving circuit 85 to open said intake and said exhaust in alternation, steering means, and operative connections between said steering means and said movable member.

3. A system for utilizing radiant energy 90 comprising in combination a receiving circuit responsive to radiant energy, a compressed fluid operated prime mover provided with an intake and an exhaust and with motion transmitting means movable 95 in contrasting directions dependent respectively upon the opening of said intake and said exhaust, and means operable through the instrumentality of said receiving circuit for controlling the opening and the closing 100 of said intake and said exhaust for effecting said movements of said motion transmitting means.

4. A system for controlling moving vessels by radiant energy comprising in combination a receiving circuit responsive to radiant energy, a compressed fluid operated prime mover provided with an intake and an exhaust and with motion transmitting means movable in contrasting directions 105 dependent respectively upon the opening of said intake and said exhaust, a vessel having steering means, and means operatively connected to said steering means and operated through the instrumentality of said receiving circuit for controlling the opening and closing of said intake and said exhaust for effecting said movements of said motion transmitting means.

5. A system for utilizing radiant energy, 120 comprising in combination a receiving circuit responsive to radiant energy, a compressed fluid operated prime mover provided with an intake and an exhaust and with motion transmitting means movable in 125 contrasting directions dependent respectively upon the opening of said intake and said exhaust, and a valve operable through the instrumentality of said receiving circuit and movable thereby into inlet-open and ex- 130

haust-open positions for effecting said movements of said motion transmitting means.

6. A system for utilizing radiant energy, comprising in combination a receiving circuit responsive to radiant energy, a compressed fluid operated prime mover provided with an intake and an exhaust and with motion transmitting means movable in contrasting directions dependent respectively upon the opening of said intake and said exhaust, and a valve operable through the instrumentality of said receiving circuit and movable thereby into inlet-open and exhaust-open and neutral positions for effecting said movements of said motion transmitting means.

7. A system for utilizing radiant energy, comprising in combination a receiving circuit responsive to radiant energy, a compressed fluid operated prime mover provided with an intake and an exhaust and with motion transmitting means movable in contrasting directions dependent respectively upon the opening of said intake and said exhaust, means for retarding the normal action of said prime mover, and a valve operable through the instrumentality of said receiving circuit and movable thereby into inlet-open and exhaust-open and neutral positions for effecting said movements of said motion transmitting means.

8. A system for controlling moving vessels by radiant energy comprising in combination a receiving circuit responsive to radiant energy, a compressed fluid operated prime mover provided with an intake and an exhaust and with motion transmitting means movable in contrasting directions dependent respectively upon the opening of said intake and said exhaust, a vessel having steering means, means operatively connected to said steering means and operated through the instrumentality of said receiving circuit for controlling the opening and closing of said intake and said exhaust for effecting said movements of said motion transmitting means and means automatically operative to stop the movement of said steering means in a position between the extreme positions of movement of said steering means.

9. A system of controlling moving bodies at a distance which consists of a receiving circuit for radiant energy, a supply of fluid under pressure, a prime mover connected with said fluid supply, a valve having a plurality of inlet and a plurality of outlet ports controlling the fluid supply to said prime mover, an electromagnet controlled by the receiving circuit and means operated by said magnet for actuating the valve.

10. A system of controlling mechanisms at a distance which consists of a moving body with a prime mover for operating the same, a supply of fluid under pressure connected with said prime mover, a valve con-

trolling the supply of fluid to said prime mover, and means for actuating said valve, comprising an electromagnet and a plurality of tuned electric circuits.

11. A system for utilizing radiant energy comprising in combination, a receiver responsive to radiant energy, a fluid operated prime mover having motion-transmitting means movable thereby in differentiated directions, means controlled by said receiver for initiating the action of said prime mover positively to effect the movement of said transmitting means in said differentiated directions, functioning means controlled by said prime mover, and means automatically controlled by said functioning means for effecting a neutral position of said controlled means.

12. A system for utilizing radiant energy comprising in combination, a receiver responsive to radiant energy, a movable body having functioning means, a fluid operated prime mover having motion transmitting means movable into differentiated positions, operative connections between said prime mover and said functioning means, a valve controlled by said receiver, and means automatically operated by said functioning means to move said valve to neutral position upon cessation of radiant impulses.

13. A system for utilizing radiant energy comprising in combination, a receiver responsive to radiant energy, a movable body having functioning means, a fluid operated prime mover having motion transmitting means movable into differentiated positions, operative connections between said prime mover and said functioning means, a rotary valve having ports and neutral positions, and connections between said valve and responsive receiver to turn said valve so as to render either its ports or its neutral positions controlling.

14. A system for utilizing radiant energy comprising in combination, a receiver responsive to radiant energy, a movable body having functioning means, a fluid operated prime mover having motion transmitting means movable into differentiated positions, operative connections between said prime mover and said functioning means, a rotary valve, connections between the responsive receiver and said valve to rotate the same, and means to turn said valve to a neutral position upon cessation of the radiant impulses.

15. A system for utilizing radiant energy comprising in combination, a receiver responsive to radiant energy, a movable body having functioning means, a fluid operated prime mover having motion transmitting means movable into differentiated positions, operative connections between said prime mover and said functioning means, a rotary valve having ports and neutral posi-

- tions, an operative connection between said responsive receiver and valve to rotate the latter, and other means automatically controlled by the functioning part to turn said 5 valve, thereby to render a neutral position thereof controlling.
16. A system for utilizing radiant energy comprising in combination, a vessel having steering mechanism, a receiver thereon responsive to radiant energy, a fluid operated prime mover having motion transmitting means movable thereby in differentiated directions, operative connections between said valve and said prime mover, a rotary valve 10 to control said prime mover, means operated by said responsive receiver to rotate said valve and other means operated by the steering mechanism to turn said valve to a neutral position.
17. A system for utilizing radiant energy comprising in combination, a receiver responsive to radiant energy, a movable body having functioning means, a fluid operated prime mover having motion transmitting means movable into differentiated positions, operative connections between said prime mover and said functioning means, a valve controlling said prime mover, means operated by said responsive receiver to move 25 said valve, and other means operated by the steering mechanism upon cessation of radiant impulses to move said valve to neutral position.
18. A system for utilizing radiant energy comprising in combination, a vessel having steering mechanism, two cylinders and pistons to move said steering mechanism respectively in opposite directions, a cylinder and piston controlling the admission of motive 30 fluid to each of said first-mentioned cylinders, a valve controlling the admission of motive fluid to both of said last mentioned cylinders, a receiver responsive to radiant energy, and operative connections between 35 the same and said valve.
19. A system for utilizing radiant energy comprising in combination, a vessel having steering mechanism, two cylinders and pistons to move said steering mechanism respectively in opposite directions, a cylinder and piston controlling the admission of motive fluid to each of said first-mentioned cylinders, a rotary valve having ports and neutral 40 positions, connections from said valve to said last-mentioned cylinders, and means responsive to radiant energy to rotate said valve.
20. A system for utilizing radiant energy comprising in combination, a vessel having steering mechanism, two cylinders and pistons to move said steering mechanism respectively in opposite directions, a cylinder and piston controlling the admission of motive fluid to each of said first-mentioned cylinders, a rotary valve having ports and neutral 45 positions, connections from said valve to said last-mentioned cylinders, and means responsive to radiant energy to rotate said valve.
21. In a steering apparatus, a compressed fluid supply, a helm, a prime mover for the helm, a valve movable to positions to alternately supply compressed fluid to one end of the prime mover, cut off the supply and thereafter supply compressed fluid to the other end of said prime mover, means to move the valve to said positions successively, and valve moving means connected to the helm to cut off the fluid supply after the successive application thereof to opposite site ends of the prime mover.
22. In a steering apparatus, a compressed fluid supply, a helm, a prime mover for the helm, a valve rotatable to positions to alternately supply compressed fluid to one end of the prime mover, cut off the supply and thereafter supply compressed fluid to the other end of said prime mover, means to move the valve to said positions successively, and valve moving means connected to the helm to cut off the fluid supply after the successive application thereof to opposite ends of the prime mover.
23. In a steering apparatus, the combination with a helm movable through a predetermined path, of means for actuating said helm, and means automatically operative to render said actuating means temporarily ineffective whenever said helm is moved into a central or neutral position.
24. In a steering apparatus the combination with a helm, of actuating means for moving said helm, a valve controlling said actuating means and operative to cause said helm to be moved either in one direction or in a contrasting direction, or to hold said helm stationary, and means automatically operative to move said valve into such a position as to hold said helm stationary whenever said helm is moved into a central position.
25. In a steering apparatus the combination with a helm, of actuating means for moving said helm, a rotary valve controlling said actuating means and operative to cause said helm to be moved either in one direction or in a contrasting direction, or to hold said helm stationary, and means automatically operative to move said valve into such a position as to hold said helm stationary whenever said helm is moved into a central position.
26. The combination with a dirigible body, of means for steering said body either in one direction or in a different direction, a source of fluid pressure carried by said body, fluid pressure means for actuating said steering means, and controlling means

rotatable step by step and in one direction only for controlling the distribution of fluid from said source to said fluid pressure means to steer said body selectively in either of said directions:

27. The combination with a dirigible body, of a source of fluid pressure carried thereby, fluid actuated means for rotating said body selectively either in one direction or in an opposite direction, and means rotatable through predetermined successive steps in one direction only for distributing fluid pressure from said source to said fluid actuated means to rotate said body selectively in either of said directions.

28. The combination with a dirigible body, of a source of fluid pressure carried thereby, fluid actuated means for rotating said body selectively either in one direction or in an opposite direction and through any desired arc in either of said directions, and means rotatable through predetermined successive steps in one direction only for distributing fluid pressure from said source to said fluid actuated means to rotate said body selectively in either of said directions, and through any desired arc in either direction.

29. The combination with a dirigible body, of a source of fluid pressure carried thereby, fluid actuated means for rotating said body selectively either in one direction or in an opposite direction, controlling means rotatable step by step and in one direction only for distributing fluid pressure from said source to said fluid actuated means to rotate said body selectively in either of said directions, and means responsive to radiant energy for rotating said controlling means.

30. The combination with a dirigible body, of a source of fluid pressure carried thereby, fluid actuated means for steering said body selectively either in one direction or in an opposite direction, controlling means rotatable step by step and in one direction only for distributing fluid pressure from said source to said fluid actuated means to steer said body selectively in either of said directions, and means responsive to radiant energy for rotating said controlling means.

31. The combination with a dirigible body, a source of fluid pressure carried thereby, fluid actuated means arranged to steer said body selectively either in one direction or in an opposite direction, and means including an electromagnet for causing the distribution of fluid pressure from said source to said fluid actuated means, the arrangement being such that by energizing said electromagnet successively the said body may be steered successively in said directions.

32. The combination with a dirigible body, a source of fluid pressure carried thereby,

fluid actuated means arranged to rotate said body selectively either in one direction or in an opposite direction, and means including an electromagnet for causing the distribution of fluid pressure from said source to said fluid actuated means, the arrangement being such that by energizing said electromagnet successively the said body may be rotated successively in said directions.

33. The combination with a dirigible body, of steering means carried thereby for steering said body selectively either in one direction or an opposite direction, of means including an element rotatable step by step and in one direction only through active and neutral positions for causing said steering means to steer said body selectively in either of said directions, and means controlled by said steering means and automatically operative to rotate said element into said neutral position whenever said steering means is moved into a central or neutral position.

34. The combination with a dirigible body, of a source of fluid pressure carried thereby, fluid actuated means for steering said body selectively either in one direction or in a different direction, and means rotatable step by step in one direction for distributing fluid pressure to said fluid actuated means to steer said body selectively.

35. The combination with a dirigible body, of a source of fluid pressure carried thereby, fluid actuated means for steering said body selectively either in one direction or in a different direction, and valve means rotatable step by step in one direction and provided with a plurality of passages for fluid for distributing fluid pressure to said fluid actuated means to steer said body selectively.

36. The combination with a dirigible body, of a source of fluid pressure carried thereby, fluid actuated means for steering said body selectively either in one direction or in a different direction, means rotatable step by step in one direction for distributing fluid pressure to said fluid actuated means to steer said body selectively, and means responsive to radiant energy for rotating said second mentioned means.

37. The combination with a dirigible body, of a source of fluid pressure carried thereby, fluid actuated means for steering said body selectively either in one direction or in a different direction, valve means rotatable step by step in one direction and provided with a plurality of passages for fluid for distributing fluid pressure to said fluid actuated means to steer said body selectively, and means responsive to radiant energy for rotating said second mentioned means.

38. The combination with a dirigible body, of a source of fluid pressure carried thereby, fluid actuated means for steering said body selectively either in one direction or in a

different direction, means rotatable step by step in one direction for distributing fluid pressure to said fluid actuated means to steer said body selectively, means responsive to 5 radiant energy for rotating said second mentioned means, and means responsive to radiant energy and including a single electromagnetic device arranged to be successively energized to rotate said second mentioned means.

39. The combination with a dirigible body, of a source of fluid pressure carried thereby, fluid actuated means for steering said body selectively either in one direction or in a 15 different direction, valve means rotatable step by step in one direction and provided with a plurality of passages for fluid for distributing fluid pressure to said fluid actuated means to steer said body selectively, means 20 responsive to radiant energy for rotating said second mentioned means, and means responsive to radiant energy and including a single electromagnetic device arranged to be successively energized to rotate said second mentioned means.

40. The combination with a plurality of separately operative fluid actuated devices, of means for actuating said devices selectively including a source of fluid pressure, 30 fluid distributing valve means rotatable step by step in one direction and arranged to distribute fluid from said source to said devices selectively, and means arranged to be repeatedly energized at the will of an operator to 35 rotate said valve means.

41. The combination with a plurality of separately operative fluid actuated devices, of means for actuating said devices selectively including a source of fluid pressure, 40 fluid distributing valve means rotatable step by step in one direction and arranged to distribute fluid from said source to said devices selectively, and means including an electromagnetic device arranged to be repeatedly 45 energized at the will of an operator to rotate said valve means.

42. The combination with a plurality of separately operative fluid actuated devices, of means for actuating said devices, said 50 means including a source of fluid pressure, fluid distributing valve means rotatable step by step in one direction, and arranged to distribute fluid from said source to said devices selectively, and means responsive to 55 radiant energy and arranged to be energized repeatedly at the will of an operator to rotate said valve means step by step to actuate said fluid selectively.

43. In a steering apparatus, the combination with fluid actuated steering means movable through a predetermined path, of a source of fluid pressure, valve means arranged to distribute fluid from said source 60 to said steering means to actuate said steer-

ing means, said valve means being movable into an active and into a neutral position, and fluid actuated means controlled by said steering means and automatically operative to move said valve into a neutral position 70 whenever said steering means is moved into a given position.

44. In a steering apparatus, the combination with fluid actuated steering means movable through a predetermined path of a source of fluid pressure, valve means arranged to distribute fluid from said source to said steering means to actuate said steering means, said valve means being movable into an active and into a neutral position, 75 and means controlled by said steering means and movable independently of said steering means and automatically operative to move said valve into a neutral position whenever said steering means is moved into a given 80 position.

45. The combination with a device movable through a predetermined path of controlling means movable into an active and into a neutral position to cause the actuation 85 of said device and to oppose the actuation of said device respectively, and means controlled by said device and movable with respect to said device and with respect to said means and automatically operative to move 90 said controlling means into a neutral position upon the movement of said device into a given position.

46. The combination with a plurality of separately operative fluid actuated devices, 100 of means for actuating said devices, said means including a source of fluid pressure, fluid distributing valve means rotatable step by step in one direction, and arranged to distribute fluid from said source to said devices selectively, and means including an electromagnetic device responsive to radiant 105 energy and arranged to be energized repeatedly at the will of an operator to rotate said valve means step by step to actuate said fluid 110 actuated devices separately and selectively.

47. The combination with means providing a plurality of separate fluid receiving chambers, of means actuated by the pressure of fluid in said chambers, a source of fluid 115 pressure, fluid distributing valve means rotatable step by step in one direction, and arranged to distribute fluid from said source to said chambers selectively, and means responsive to radiant energy and arranged to be energized repeatedly at the will of an operator to rotate said valve means step by step, and means to retard the distribution 120 of fluid pressure from said source to one of said chambers after said valve means has been moved into such a position as to cause the ultimate distribution of fluid pressure from said source to said chamber.

48. The combination with means providing a plurality of separate fluid receiving

chambers, of means actuated by the pressure of fluid in said chambers, a source of fluid pressure, fluid distributing valve means rotatable step by step in one direction and 5 arranged to distribute fluid from said source to said chamber selectively, means arranged to be repeatedly energized at the will of an operator to rotate said valve means, and means to retard the distribution of fluid 10 from said source to one of said chambers after said valve means has been rotated into such a position as to cause the ultimate distribution of fluid to said chamber.

49. The combination with means providing 15 a plurality of separate fluid receiving chambers, of means actuated by the pressure of fluid in said chambers, a source of fluid pressure, fluid distributing valve means rotatable step by step in one direction and 20 arranged to distribute fluid from said source to said chambers selectively, and means arranged to be repeatedly energized at the will of an operator to rotate said valve means, the construction and arrangement being 25 such that the distribution of fluid to at least one of said chambers will be effected only after said valve means has been permitted to remain for an appreciable and otherwise unnecessary length of time in such a position 30 as to cause the ultimate distribution of fluid pressure from said source to said chamber.

50. The combination with means providing 35 a plurality of separate fluid receiving chambers, of means actuated by the pressure of fluid in said chambers, a source of fluid pressure, fluid distributing valve means rotatable step by step in one direction and arranged to distribute fluid from said source 40 to said chambers selectively, and means responsive to radiant energy and arranged to be energized repeatedly at the will of an operator to rotate said valve means step by step, the construction and arrangement being 45 such that the distribution of fluid to at least one of said chambers will be accomplished only after said valve means has been permitted to remain for an appreciable and otherwise unnecessary length of time in such 50 a position as to cause the ultimate distribution of fluid to said chamber.

51. The combination with a source of fluid supply, of a plurality of independently movable elements, a valve arranged to connect 55 said elements with said source of supply and operative to cause the actuation of any one of said elements selectively, and means responsive to radiant energy for actuating said valve.

52. The combination with a source of fluid supply, of a plurality of independently movable elements, a valve arranged to connect 60 said elements with said source of supply and operative to cause the actuation of any one of said elements independently of any other

65 of said elements, and means responsive to radiant energy for actuating said valve.

53. The combination with means for supplying fluid pressure, of a plurality of separately operative fluid-actuated prime movers, 70 a valve arranged to connect said prime movers with said means and operative to cause the actuation of any one of said prime movers selectively, and means responsive to radiant energy for actuating said valve. 75

54. The combination with means for supplying fluid pressure, of a plurality of separately operative fluid-actuated prime movers, 80 a rotary valve arranged to connect said prime movers with said means and operative to cause the actuation of any one of said prime movers selectively, and means responsive to radiant energy for actuating said valve.

55. The combination with means for supplying fluid pressure, of a plurality of separately operative fluid-actuated prime movers, 85 a valve arranged to connect said prime movers with said means and operative to cause the actuation of any one of said prime movers selectively, means responsive to radiant energy for actuating said valve, and means to retard the initiation of the actuation of one of said prime movers after said valve has been moved into such a position 90 as to cause the ultimate actuation of said prime mover. 95

56. The combination with means for supplying fluid pressure, of a plurality of separately operative fluid-actuated prime movers, 100 a rotary valve arranged to connect said prime movers with said means and operative to cause the actuation of any one of said prime movers selectively, means responsive to radiant energy for actuating said valve, 105 and means to retard the initiation of the actuation of one of said prime movers after said valve has been moved into such a position as to cause the ultimate actuation of said prime mover. 110

57. The combination with means for supplying fluid pressure, of a plurality of separately operative fluid-actuated devices, a valve arranged to connect said devices with said means and operative to cause the actuation of any one of said devices selectively, 115 means responsive to radiant energy for actuating said valve, and means to retard the initiation of the actuation of one of said fluid operative devices after said valve has been 120 moved into such a position as to cause the ultimate actuation of said device.

58. The combination with means for supplying fluid pressure, of a plurality of separately operative fluid-actuated devices, a rotary valve arranged to connect said devices with said means and operative to cause the actuation of any one of said devices selectively, 125 means responsive to radiant energy for actuating said valve, and means to retard 130

the initiation of the actuation of one of said fluid operative devices after said valve has been moved into such a position as to cause the ultimate actuation of said device.

- 5 59. The combination with a plurality of separately operative fluid actuated devices, of means for actuating said devices, said means including means for supplying fluid pressure, fluid distributing valve means rotatable step by step and arranged to distribute fluid from said second-mentioned means to said devices selectively, means responsive to radiant energy and arranged to be energized repeatedly at the will of an operator to 70 rotate said valve means step by step to actuate said fluid actuated devices separately and selectively, and means to retard the initiation of the actuation of one of said fluid-actuated devices after said valve means has been moved into such a position as to cause the ultimate actuation of said fluid-actuated device.

60. The combination with a plurality of separately operative fluid actuated devices, 25 of means for actuating said devices, said means including means for supplying fluid pressure, fluid distributing valve means rotatable step by step in one direction, and arranged to distribute fluid from said second-mentioned means to said devices selectively, means responsive to radiant energy and arranged to be energized repeatedly at the will of an operator to rotate said valve means step by step to actuate said fluid-actuated devices separately and selectively, and means to retard the initiation of the actuation of one of said fluid-actuated devices after said valve means has been moved into such a position as to cause the ultimate actuation of said fluid-actuated device.

61. The combination with a plurality of separately operative fluid actuated devices, of means for actuating said devices selectively including means for supplying fluid pressure, fluid distributing valve means movable step by step in one direction through a plurality of steps and arranged to distribute fluid from said second-mentioned means to said devices selectively, means arranged to be repeatedly energized at the will of an operator to rotate said valve means, and means to retard the initiation of the actuation of one of said fluid-actuated devices after said valve means has been rotated into such a position as to cause the ultimate actuation of said fluid-actuated device.

62. The combination with a plurality of separately operative fluid-actuated devices, of means for actuating said devices selectively including means for supplying fluid pressure, fluid distributing valve means movable step by step in one direction through a plurality of steps and into a plurality of predetermined positions and arranged to distribute fluid from said second-mentioned

means to said devices selectively, means arranged to be repeatedly energized at the will of an operator to rotate said valve means, and means to retard the initiation of the actuation of one of said fluid actuated devices after said valve means has been rotated into such a position as to cause the ultimate actuation of said fluid-actuated device.

63. The combination with a plurality of separately operative fluid-actuated prime movers, of means for actuating said devices selectively including means for supplying fluid pressure, fluid distributing valve means rotatable step by step in one direction 80 through a plurality of steps and arranged to distribute fluid from said second-mentioned means to said devices selectively, and means arranged to be repeatedly energized at the will of an operator to rotate said valve 85 means.

64. The combination with a plurality of separately operative fluid-actuated prime movers, of means for actuating said devices selectively including means for supplying 90 fluid pressure, fluid distributing valve means rotatable step by step in one direction through a plurality of steps and into a plurality of predetermined operative positions and arranged to distribute fluid from said 95 second-mentioned means to said devices selectively, and means arranged to be repeatedly energized at the will of an operator to rotate said valve means.

65. The combination with a plurality of separately operative fluid-actuated prime movers, of means for actuating said devices selectively including means for supplying fluid pressure, fluid distributing valve means rotatable step by step in one direction 100 through a plurality of steps and arranged to distribute fluid from said second-mentioned means to said devices selectively, and means arranged to be repeatedly energized at the will of an operator to rotate said 105 valve means, the construction and arrangement being such that at least one of said prime movers will be actuated only after said valve means has been permitted to remain for an appreciable and otherwise unnecessary length of time in such a position as to cause the ultimate actuation of said fluid-actuated device.

66. The combination with a plurality of separately operative fluid-actuated prime movers, of means for actuating said devices selectively including means for supplying fluid pressure, fluid distributing valve means rotatable step by step in one direction 120 through a plurality of steps and into a plurality of predetermined operative positions and arranged to distribute fluid from said second-mentioned means to said devices selectively, and means arranged to be repeatedly energized at the will of an operator to 125 130

rotate said valve means, the construction and arrangement being such that at least one of said prime movers will be actuated only after said valve means has been permitted to remain for an appreciable and otherwise unnecessary length of time in such a position as to cause the ultimate actuation of said fluid-actuated device.

67. The combination with a plurality of separately operative fluid-actuated prime movers, of means for actuating said devices selectively, said means including means for supplying fluid pressure, unitary fluid distributing valve means movable into a plurality of predetermined operative positions and arranged to distribute fluid from said source to said devices selectively, and means responsive to radiant energy and arranged to be energized repeatedly at the will of an operator to actuate said valve means and to cause the operation of any one of said prime movers separately and selectively.

68. The combination with a plurality of separately operative fluid-actuated prime movers, of means for actuating said devices selectively, said means including means for supplying fluid pressure, unitary fluid distributing valve means movable through a plurality of predetermined steps in one direction and into a plurality of predetermined operative positions and arranged to distribute fluid from said source to said devices selectively, and means responsive to radiant energy and arranged to be energized repeatedly at the will of an operator to actuate said valve means and to cause the operation of any one of said prime movers separately and selectively.

69. The combination with a plurality of separately operative fluid-actuated prime movers, of means for actuating said devices selectively, said means including means for supplying fluid pressure, unitary fluid distributing valve means movable into a plurality of predetermined operative positions and arranged to distribute fluid from said source to said devices selectively, and means responsive to radiant energy and arranged to be energized repeatedly at the will of an operator to actuate said valve means and to cause the operation of any one of said prime movers separately and selectively, the construction and arrangement being such that at least one of said fluid-actuated devices will be actuated only after said valve means has been permitted to remain for an appreciable and otherwise unnecessary length of time in such a position as to cause the ultimate actuation of said fluid-actuated device.

70. The combination with a plurality of separately operative fluid-actuated prime movers, of means for actuating said devices selectively, said means including means for supplying fluid pressure, unitary fluid dis-

tributing valve means movable through a plurality of predetermined steps in one direction and into a plurality of predetermined operative positions and arranged to distribute fluid from said source to said devices selectively, and means responsive to radiant energy and arranged to be energized repeatedly at the will of an operator to actuate said valve means and to cause the operation of any one of said prime movers separately and selectively, the construction and arrangement being such that at least one of said fluid-actuated devices will be actuated only after said valve means has been permitted to remain for an appreciable and otherwise unnecessary length of time in such a position as to cause the ultimate actuation of said fluid-actuated device.

71. In a system for receiving radiant energy, the combination with a single element responsive to radiant energy, of a plurality of separately operative fluid-actuated prime movers arranged to be selectively controlled as a result of the action of said element.

72. In a system for receiving radiant energy, the combination with a single open aerial circuit responsive to radiant energy, of a plurality of separately operative fluid-actuated prime movers arranged to be selectively controlled as a result of the action of said open aerial circuit.

73. In a system for receiving radiant energy, the combination with a plurality of separately operative fluid-actuated prime movers, of a single element responsive to radiant energy, and means interposed between said element and said prime movers, and controlled by said element, for selectively operating said prime movers.

74. In a system for receiving radiant energy, the combination with a plurality of separately operative fluid-actuated prime movers, of a single open aerial circuit responsive to radiant energy, and means interposed between said open aerial circuit and said prime movers, and controlled by said open aerial circuit, for selectively operating said prime movers.

75. A system for utilizing radiant energy, comprising in combination, a receiving circuit responsive to radiant energy, a plurality of fluid-operated prime movers, and means controlled by said circuit for effecting the independent operation of said prime movers.

76. A system for utilizing radiant energy in the form of electric waves, comprising in combination, a receiving circuit responsive to electric waves, a plurality of fluid-operated prime movers pertaining to a movable body, and means controlled by said circuit for effecting the independent operation of said prime movers.

77. A system for utilizing radiant energy in the form of electric waves comprising in combination, a receiving circuit responsive

to electric waves, a plurality of fluid-operated prime movers pertaining to a movable body and functioning in the control thereof, and means controlled by said circuit for effecting the independent operation of said prime movers.

78. A system for utilizing radiant energy, comprising in combination, a receiver responsive to radiant energy, a plurality of fluid-operated prime movers, and a fluid pressure controlling valve operated by said receiver to effect the independent operation of said prime movers.

79. A system for utilizing radiant energy, comprising in combination, a receiver responsive to radiant energy, a plurality of fluid-operated prime movers upon a movable body and functioning in the control thereof, and a fluid pressure controlling valve operated by said receiver to effect the independent operation of said prime movers.

80. A system for utilizing radiant energy, comprising in combination, a receiver responsive to radiant energy, a plurality of fluid-operated prime movers upon a movable body and functioning in the control thereof, and a rotary, pneumatic valve having active and neutral positions, and operated by said receiver to effect the independent operation of said prime movers.

81. A system for utilizing radiant energy, comprising in combination, a receiver responsive to radiant energy, a plurality of fluid-operated prime movers upon a movable body and functioning in the control thereof, and a fluid pressure controlling valve operated by said receiver to effect the operation of any of said prime movers or the skipping thereof.

82. A system for utilizing radiant energy, comprising in combination, a receiver responsive to radiant energy, a plurality of fluid-operated prime movers upon a movable body and functioning in the control thereof, a fluid pressure controlling valve operated by said receiver to effect the independent operation of said prime movers and retarding mechanism co-acting with said prime movers to retard the operation thereof upon movement of said valve.

83. A system for utilizing radiant energy, comprising in combination, a receiver responsive to radiant energy, a plurality of fluid-operated prime movers upon a movable body and functioning in the control thereof, a fluid-pressure controlling valve operated by said receiver to effect the independent operation of said prime movers, and a retarding device co-acting with one at least of said prime movers and operated by motive fluid admitted upon movement of said fluid pressure controlling valve.

84. A system for utilizing radiant energy,

comprising in combination, a receiver responsive to radiant energy, a plurality of fluid-operated prime movers upon a movable body and functioning in the control thereof, a fluid pressure controlling valve operated by said receiver to effect the independent operation of said prime movers and a retarding device for each of said prime movers and operated by motive fluid admitted from said fluid pressure controlling valve.

85. A system for utilizing radiant energy, in the form of electric waves comprising in combination, a receiver responsive to radiant energy, a craft having a plurality of fluid-operated prime movers functioning in the control thereof, rudder mechanism for said craft, and fluid-pressure controlling mechanism operated by said receiver to effect the independent operation of said prime movers and including means automatically to center the rudder.

86. A system for utilizing radiant energy in the form of electric waves comprising in combination, a craft having a plurality of fluid-operated prime movers functioning in the control thereof, rudder mechanism for said craft, a fluid pressure controlling valve having active and neutral positions and operated by said receiver to effect the independent operation of said prime movers, and co-acting mechanism to lock the system with the rudder in central position or in a position at either side of the center, by movement of the valve into neutral position.

87. A system for utilizing radiant energy in the form of electric waves comprising in combination, a craft having a plurality of fluid-operated prime movers functioning in the control thereof, rudder mechanism for said craft, a valve having active and neutral positions and operated by said receiver to effect the independent operation of said prime movers, and co-acting means to effect the movement of said valve to neutral position by movement of the rudder.

88. A system for utilizing radiant energy in the form of electric waves, comprising in combination, a craft having a plurality of fluid-operated prime movers functioning in the control thereof, rudder mechanism for the craft, a valve having active and neutral positions and operated by said receiver to effect the independent operation of said prime movers, and co-acting means to effect the locking of the system and thereby to hold the rudder in any desired position.

This specification signed and witnessed this 11th day of January, A. D. 1913.
